EDWIN G. BULGIN, OF VIENNA, NEW JERSEY.

Letters Patent No. 79,546, dated July 7, 1868.

IMPROVED CHEESE-SAFE, GAUGE, AND CUTTER.

The Schedule referred to in these Letters Patent and making part of the same.

TO ALL WHOM IT MAY CONCERN:

Be it known that I, EDWIN G. BULGIN, of Vienna, in the county of Warren, and State of New Jersey, have invented certain new and useful Improvements in a Safe, Gauge, and Cheese-Cutting Apparatus; and the following is a full, clear, and exact description of the same, reference being had to the drawings accompanying this specification and forming a part of the same, in which—

Figure 1 shows a perspective view of my improved safe with the cutting-apparatus and gauge.
Figure 2 shows a front view of the same.

Figure 3 is a sectional view of the same, with a portion of the safe removed to show a cheese in position. The object of my invention is to supply grocers and retail dealers of cheese with facilities for cutting up in a more symmetrical manner, and also for estimating more accurately the weight of the piece to be cut off, so that, according to the weight of the cheese placed in the safe, the proportion of any given quantity of it may be determined by a gauge or index.

My invention consists in a new arrangement and combination of peculiar mechanism, applied to a safe for holding cheese for retailing, by which the cheese may be accurately divided by a scale or index, and cut to any desired weight.

I use, for the bottom of the safe, a piece of board, cut circular, as seen at A, fig. 1, of such a size as deemed necessary to hold any cheese, and from two opposite points in its circumference erect two posts, B and C, figs. 2 and 3, and connect the upper ends by a horizontal beam.

At a point on the circumference of the board A, midway between the posts B and C, I place another post, D, and these three posts serve to support the semicircular top or cover E, which covers one-half of the safe. This top E is firmly fixed to the posts B and C, and the beam which connects them, and the post D passes up through it, for purposes hereafter to be described.

To the beam connecting the posts B and C is hinged the semicircular cover F, which is made with a light framework of wood and wire cloth, in the same manner as ordinary safes for holding cheese, and can be opened upwards, as seen in figs. 1 and 3, so as to admit the cheese.

The remaining side of the safe is enclosed by two sliding doors, G and H, fig. 1, which slide right and left from the post D, being moved by the knobs a a, as desired. These doors slide in grooves, one formed in the upper surface of the board A, and the other in the lower surface of the top, E, and, when the cover F is closed, can be pushed back so as to nearly meet on that side, and in order that they may so slide back, the cover F must be made a little smaller, that they may move outside of it.

The parts above described form a most perfect safe for keeping and preserving cheese from insects, &c., and in order to fit it for a cutter and measurer, I make use of additional parts.

A little above the bottom of the safe I place a circular table, I, which is secured to the centre of the bottom, A, by a bolt or screw, passing through the centre of each, in such a manner that it is free to turn upon its own centre, being supported by the block b, and three or more friction-rollers c c c, so that it is free to turn easily in either direction, when desired. On this table, I, the cheese is placed, so that its centre will be over the centre of said table.

On the top of the beam connecting the posts B and C, and midway between its ends, I place the post J, and to the top of this post I pivot the lever d, which works the cutting-knife K, being connected with it by a rod, g, as shown in fig. 1. This knife K is made of a thin plate of galvanized steel, and extends from the post D to the post J, sliding in grooves cut in said posts to receive it, and is of sufficient vertical length to reach the table I, and still leave a portion above the top, E, of the safe.

In order to allow the knife to pass down, a thin slot is cut in the top, E, and the groove on the inner face of the post D extends down its whole length on to the table I, and by the action of the lever the knife may be easily and quickly forced down through any cheese that may be on the table I, and as readily withdrawn from the same.

At the right of the knife, on the top of the cover E, and a little way from the circumference, I place a graduated plate, L, in which slides another plate, M, carrying an index or pointer, e.

The plate L is graduated as desired, and the index e, projecting over it, enables any number of the equal parts to be read off with accuracy.

The plate M, in addition to the index e, carries a marker, i, figs. 2 and 3, which projects downwards through the cover to the cheese below, and its object is to indicate the point at which the cut edge of the cheese should be stopped, as the table carrying the cheese is revolved from left to right, in order that the portion indicated by the pointer e may be cut off by the knife K.

A narrow slit is cut in the cover, so as to allow this marker, i, to be moved backwards and forwards with the plate to which it is attached, and a set-screw, h, is used to fasten and retain said plate L at any desired point.

At the left of the knife is the screw f, which passes through the cover, and downward to the top of the cheese, its lower end being terminated by a broad and flat head or roller, to prevent the cheese from being lifted off the table I by the withdrawal of the knife.

As cheeses are of different thicknesses and diameters, the weight of the whole cheese being determined, any proportional part may be indicated, so that one, two, three, five or more pounds or fractional parts of pounds may be determined very nearly, so that the quantity ordered will be cut in one symmetrical piece, instead of two or three irregular, uncouth-looking pieces.

Having thus fully described my invention, what I claim as new, and desire to secure by Letters Patent, is—

1. The sliding doors G and H, as arranged and combined with a rotary bottom and a cutting-apparatus, for the purposes set forth.

2. The arrangement and combination of the cutting-knife K, hand-lever d, regulating-screw f, with a cheese-safe, as described, for the purposes herein set forth.

3. The graduated scale or index-plate L, the sliding plate M, with its index-finger e and the marker i, as connected with a cheese-safe, for the purpose set forth.

EDWIN G. BULGIN.
